Design No. 3,273, dated December 1, 1868.

DESIGN FOR PRINTERS' TYPE.

The Schedule referred to in these Letters Patent and making part of the same.

To all whom it may concern:

Be it known that I, ANDREW LITTLE, of the city, county, and State of New York, have originated and produced a new Design for Printing-Type, of which the following is a full, clear, and exact description, reference being had to the accompanying specimens, making part of this specification, in which the entire alphabet of the large and small letters is shown, the figures

and signs employed being similar, in style, design, and ornamentation, to those shown.

What I claim as my production, and desire to secure by Letters Patent, is—

The design for printing-type, as shown and set forth.

Witnesses: ANDREW LITTLE.
